UNITED STATES PATENT OFFICE.

JULIO GUIMARÃES, OF BERLIN, GERMANY.

OIL-LAMP.

SPECIFICATION forming part of Letters Patent No. 684,227, dated October 8, 1901.

Application filed April 16, 1901. Serial No. 56,147. (No model.)

To all whom it may concern:

Be it known that I, JULIO GUIMARÃES, a citizen of Argentina, residing in Berlin, in the Kingdom of Prussia and Empire of Germany, have invented certain new and useful Improvements in Oil-Lamps, of which the following is a specification.

This invention relates to improvements in oil-lamps; and the object of the invention is to provide a lamp of this kind which will give a very strong and steady light without the use of a chimney or other protection for the flame; and the invention consists in the combination, in a lamp, with an oil-reservoir, of an air-supply tube extending upwardly through the reservoir, a reservoir-tube within said air-supply tube and communicating with the reservoir, a wick-tube secured to the upper end of said reservoir-tube, a socket secured to the reservoir at the upper end of the air-supply tube, a plate on said socket extending outwardly beyond the same and inwardly to the wick-tube, an inner cap supported on said plate and having its lower edge opposite the socket, and an outer cap supported on said plate over the inner cap, said plate being provided with perforations within the inner cap and between the inner and outer caps and said socket being provided with perforations communicating with the space below the inner portion of said plate.

In the accompanying drawings, Figure 1 is a vertical central section through a lamp embodying my invention. Fig. 2 is a top view of the lamp shown in Fig. 1, and Fig. 3 is a section on line A B, Fig. 1.

Similar letters of reference indicate corresponding parts.

Referring to the drawings, *a* indicates the reservoir of the lamp, which is provided with a central air-supply tube *b*, extending upwardly through the same. Within the tube *b* is arranged a reservoir-tube *c*, which is closed at the bottom and connected with the reservoir by connecting-walls *d*, as shown in Figs. 1 and 3. The tubes *b* *c* are perforated between the walls *d*, so as to allow the liquid fuel to pass from the reservoir into the reservoir-tube *c*. A flat burner-tube *f* is secured on the upper end of the tube *c* and contains a flat wick *g*, which can be raised or lowered by turning the spindle *h*. Below the upper

edge of the burner is arranged a dished plate *i*, which extends inwardly into contact with the burner-tube *f*, and which is supported by a downwardly-extending socket *k*, soldered or otherwise secured thereto, and which fits over the upwardly-projecting edge *l* of the reservoir *a*. On the plate *i* rests an inner burner-cap, the lower diameter of which corresponds to the diameter of the cylindrical socket *k* and is arranged opposite the same, and over said cap is arranged another slotted cap of larger diameter, which is also supported on the plate *i*.

The foot *n* of the lamp is provided with openings *o*, through which atmospheric air enters and passes in upward direction through the channel between the tubes *b* and *c*. The plate is perforated within the cap *p* and also between the caps *p* and *r*, and the socket *k* is provided with openings communicating with the space below the plate *i* at its inner portion opposite the cap *p*. Through these openings *m* of the plate and socket air enters and mingles with the air supplied from below through the foot *n*, passing thence through the plate *i* for supplying air to the flame within the inner cap, while the air entering through the outer perforations of the plate *i* passes into the flame between the caps *p* and *r*. To the flame a considerable quantity of oxygen gas is thus supplied through the central air-tube and the perforations, so that without the use of an incandescent mantle or a chimney or other protecting means for the flame a very intense and almost white flame is obtained.

Having thus described my invention, I claim as new and desire to secure by Letters Patent—

In an oil-lamp, the combination, with an oil-reservoir, of an air-supply tube extending upwardly through the same, a reservoir-tube within the air-supply tube and communicating with the reservoir, the channel between said tubes communicating through the foot of the lamp with the outside air, a wick-tube secured to the upper end of said reservoir-tube, a socket secured to the reservoir at the upper end of the air-supply tube, a plate on said socket extending outwardly beyond the same and inwardly to the wick-tube, an inner cap supported on said plate and having its lower edge opposite said socket, and an outer

22

cap supported on said plate over the inner cap, said plate being provided with perforations within the inner cap and between the inner and outer caps, and said socket being provided with perforations communicating with the space below the inner portion of said plate, substantially as set forth.

In testimony that I claim the foregoing as my invention I have signed my name in presence of two subscribing witnesses.

JULIO GUIMARÃES.
